UNITED STATES PATENT OFFICE.

MARTIN O. REHFUSS, OF PHILADELPHIA, PENNSYLVANIA, ASSIGNOR TO F. W. MAURER & SONS CO., OF PHILADELPHIA, PENNSYLVANIA, A CORPORATION OF PENNSYLVANIA.

BALL-FRINGE MACHINE.

Application filed July 8, 1927. Serial No. 204,314.

This invention relates to machines for making what is commonly known as "ball fringe" i. e. a tape having a series of loops extending laterally from one of its edges and spaced at predetermined intervals longitudinally of the tape; each loop supporting a ball consisting of a plurality of strands of soft twisted yarn bound together at the common center of the ball by a wire, or other securing means, which also passes through the aforesaid loop and secures the ball to the loop.

With machines in general use at the present time, it is necessary to feed the tape to the ball making and securing mechanism by hand, placing each individual loop on what is known as the forming horn of the machine. This operation is necessarily slow, therefore, the production of fringe on any given machine is low, and further necessitates a separate operator for each machine.

The principal object of my invention is to replace the manual tape feeding operation by automatic mechanism for successively placing the loops on the forming horn, removing the loop, with a finished ball attached thereto, from the horn, and automatically advancing the tape to permit the efficient accomplishment of these operations.

In the tape in general use, the threads forming the two sides of the respective loops lie in the same general plane, which is substantially common with the plane of the body of the tape. With this formation of the tape, the adoption of automatic mechanism for feeding the tape and automatically placing the loops on the ball forming horn would be practically impossible. I have overcome this objection, by producing a tape in which the general plane of the loop extends substantially at right angles to the plane of the body of the tape, and which forms the subject matter of a co-pending application, Serial No. 152,391, filed December 3, 1926.

In the hand fed machine, the ball forming horn was of a curved construction to facilitate the manual placing of the loops on the horn. I have replaced this curved forming horn with a straight horn.

The details of my invention will be fully disclosed hereinafter, reference being had to the accompanying drawings, of which:

Fig. 1 is a plan view of a ball fringe machine having my automatic feeding mechanism attached thereto;

Fig. 2 is a front elevation of the machine shown in Fig. 1;

Fig. 3 is an enlarged plan view of the feeding mechanism, forming the subject of the present application;

Fig. 4 is a sectional elevation taken on the line 4—4, Fig. 3;

Figs. 5 and 6 are sectional elevations of various details of the machine;

Figs. 7 to 14 inclusive are plan views illustrating the various successive operations effected during the formation of a ball and the removal of the loop which supports the finished ball from the forming horn; and

Figs. 7^a to 14^a inclusive are elevational views of the mechanism shown in and corresponding to Figs. 7 to 14 respectively.

Referring to Figs. 1 to 5 of the drawings, the main rigid frame or bed plate of a "ball fringe" machine is illustrated at 1, being provided with a plurality of bearings 2, 3, 4, 5, 6 and 7. A main operating and cam shaft 10 is rotatably mounted in the bearings 2 and 3. A second cam shaft 11 is rotatably mounted in the bearings 4 and 5, parallel to the shaft 10. A connecting cam shaft 12 is rotatably mounted in the bearings 6 and 7 and extends at right angles to, and between the shafts 10 and 11. The shafts 10 and 12 are connected by a pair of cooperating mitre gears 13 and 14, and the shafts 11 and 12 are connected by a pair of cooperating mitre gears 15 and 16.

In a bearing 20, formed adjacent the front edge of the rigid frame 1 intermediate the cam shafts 10 and 11, is slidably mounted a vertically movable hollow post 21 having a head 22 rigidly secured to its upper end, and a collar 23 rigidly secured to its lower end. Levers 24, 24 are pivoted at 24^a to depending extensions of the rigid frame 1. The levers 24 are each pivotally connected at one of its ends to the collar 23, and at its opposite end to a bifurcated link 25. The forks of the bifurcated link 25 are slotted at 26 for the accommodation of the cam shaft 12, which is provided with a cam 27 engaging a roller 28 rotatably mounted in the link 25 intermediate the forks thereof. Rotation of the shaft 12 will lower the post 21 in its bearing 20. A spring 29 is adapted to raise the post 21, and maintain the roller 28 in operative contact with the cam 27.

The post head 22 is provided with integral lateral extensions 30 and 31, which form

guideways for the following ball forming mechanisms.

Slidably mounted in the extension 30 is a ball forming plate 35, provided at its inner end, adjacent the post 21, with a pair of parallel longitudinally extending horns 36 and 37. The inner adjacent edges of the horns 36 and 37 are convergent, forming a throat 38 therebetween into which the loosely twisted 10 strands of ball forming yarn *z* are adapted to be pressed. The convergent edges of the horns 36 and 37 are each provided with a wire receiving groove 39 and 40 respectively, which extends along said convergent edge 15 from the point of the respective horn into the said throat and therearound to a point within the opposite convergent edge, the two grooves, at the points of the horns, lying in a substantially horizontal plane, and the portions 20 of the groove within the throat lying in adjacent substantially horizontal planes, parallel one with the other.

The horn 37 is adapted to receive, successively, the loops *y* of the fringe, the tape body 25 *x* thereof being fed past said horn in substantially a horizontal plane; the loops *y* occupying a vertical plane permits them to be slipped over the horn 37 as the tape *x* is advanced relative to the horn. A cooperating 30 presser plate 41 is slidably mounted in the extension 31 of the post head 21, and is provided with a curved end 42 in which is formed a horizontal wire engaging groove 43.

The ball forming plate 35 is provided with 35 a head 44 engaged and operated by a cam 45 on the cam shaft 10, a spring 46 returning the plate to its normal inoperative position. The presser plate 41 is provided with a similar head 47 engaged by a cam 48 on the 40 cam shaft 11, a spring 49 returning this plate to its normal inoperative position.

Rigidly secured to the upper face of the bed plate 1 is a bracket 50, to which is secured a guide 51 for the ball forming yarn 45 *z*, a spring wire 52 acting as a brake against the said yarn to retain it in any position to which it may be moved in the guide 51.

The yarn *z* passes through an eye 53 formed in an arm 54.

50 The arm 54 is pivoted at 55 to a bracket 56 rigidly secured to the bed plate 1. One end of the arm 54 operatively engages the head 57 of a vertically movable anvil 58 which is slidably mounted in the bracket 50. The 55 opposite end of arm 54 is engaged by an operating cam 59 secured to the cam shaft 10 by means of which the anvil 58 is lowered, a spring 60 acting to return the anvil to its raised position.

60 The balls formed from the yarn *z* are secured to the fringe loops *y* by a wire ring *w*, which is fed in a horizontal plane, in a continuous length, into the path of the ball forming plates 35 and 41, at a point immediately adjacent the anvil 58, passing through

a hardened steel bushing 61 rigidly held in the bracket 50. The bushing 61 acts as one element of a shear, for cutting the continuous length of wire into short pieces of predetermined length, the other element of the shear 70 comprises a blade 62 slidably mounted in the head extension 31. A pin 63 extends downwardly from the blade 62, through the head extension 31, and is engaged by one end of a bar 64 slidably mounted in a guideway 65 75 on the bed plate 1. The opposite end of the sliding bar 64 is provided with a head 66 engaged by a cam 67 on the cam shaft 11, which moves the blade 62 in a direction to cooperate with the hardened steel bushing 61 to shear the wire, a spring 68 returning these elements to their normal positions and maintaining the bar head 66 in operative contact with the cam 67.

The wire *w* is fed forward a predetermined distance to measure the length of a portion thereof sufficient to form one of the ball retaining rings, by a cam 70 secured to the cam shaft 12, which engages a lug 71 on a wire feeding head 72, slidably mounted on the bed plate 1. The wire feeding head 72 comprises a substantially rigid finger 73 and a relatively movable finger 74, by means of which the wire *w* may be gripped between the two fingers during the forward or feeding movement of the head 72 and released therefrom during the rearward movement thereof.

The movable finger 74 is pivotally and slidably mounted on a horizontally disposed rod 75 supported by brackets 76, 76 secured to the bed plate 1, and has an arm 77 adapted to be held in operative engagement with a cam 78 on the cam shaft 11. The finger 73 consists of a spring plate secured at one of its ends to the under side of the arm 77 of the movable finger 74, its opposite end slidably resting on a bracket 79 secured to the bed plate 1. The resiliency of the spring plate comprising the finger 73 maintains the arm 77 in contact with the cam 78.

As the cam 78 rotates, the arm 77 rides onto the low portion thereof permitting the finger 74 to be moved away from the finger 73, due to the resiliency of the material of which the finger 73 is composed, to release the grip on the wire *w*. At the same time, a spring 80 returns the head 72 to its rearmost position, and maintains the lug 71 thereof in contact with the head advancing cam 70, on the cam shaft 12. The cam 78 then operates the finger 74 to again grip the wire *w* for a subsequent feeding of the said wire.

Slidably mounted within the extensions 30 and 31 respectively is a pair of ball yarn shear blades 81 and 82, each of which are provided with a vertically projecting pin 83 and 84 respectively. The pins 83 and 84 are respectively engaged by one end of a lever 85 and 86, pivoted at 87 and 88 to the bed 125 130

plate 1. The opposite end of each of the levers 85 and 86 are respectively engaged by cams 89 and 90, secured to the cam shaft 12. A spring 91 is connected at its opposite ends to and extends between the cam engaging ends of the levers 85 and 86, thereby maintaining these arms in operative engagement with their respective cams, and tending to move the shear blades 81 and 82 to their 10 operative or separated positions.

The machine so far as described is in general use, with the exception of the straight loop receiving horn 37 of the ball forming plate 35, the loop receiving horn in the old 15 machines being of a curved construction as above noted. These old machines required the manual feeding of the tape to the machine and the placing of the loops on, and their subsequent removal from, the curved horn 20 used in these machines, by hand.

The object of my present invention is to eliminate these manual operations, and to provide for the automatic mechanical feeding of the tape, the automatic placing of the 25 loops on the straight horn of my present machine, and the subsequent automatic removal of the loops from the horn with a formed ball attached to each one thereof.

The mechanism comprising the features of 30 my invention, see Figs. 3 and 4, consists of a bearing 100 rigidly secured to the head 22 of the vertically slidable post 21. In the bearing 100 is rotatably mounted a pair of parallel shafts 101 and 102. On one end of 35 the shaft 101 is rigidly secured a tape feed wheel 103, and on the corresponding end of the shaft 102 is rigidly secured a presser wheel 104, between which and the feed wheel 103 the body tape α is gripped.

40 The said body tape passes from a source of supply to and between a set of straightening rollers 105, 106 and 107, each of which is rotatably mounted on a common support 108, secured to the base plate 1. These rollers 45 move all wrinkles from the body tape α , and arrange the said tape in a substantially vertical plane, with the loops γ thereof positioned above the tape, and are adapted to retard the advancement of the tape, thus maintaining it under tension between the gripping point of the cooperating feed and presser wheels 103, 104 and the set of rollers 105, 106, 107.

50 The tape α advances from the roller 107 in a vertical plane to a vertically extending guide 109, which is secured to the bed plate 1 adjacent the wheels 103, 104.

The tape α , between the guide 109 and the upper side of the periphery of the feed wheel 55 103, is twisted from a vertical plane, at the guide 109, to a substantially horizontal plane, at the said upper side of the periphery of the feed wheel 103. At this point the loops γ , the general plane of which is at right angles 60 to the plane of the tape body α , are carried

into the path of, and are placed on the outer end of, the straight horn 37 of the ball forming plate 35, the body tape α being supported by the wheel 103 in a plane extending through the center of the horn 37 and 70 plate 35.

After passing around a portion of the periphery of the feed wheel 103 and over a portion of the periphery of the presser wheel 104, the finished fringe, consisting of the 75 body tape with the finished balls attached to the loops γ thereof, passes through the hollow post 21 to any suitable receiving receptacle.

The shaft 102 is carried in journal blocks 80 110, 110, slidably mounted slots 111 formed in the bearing 100 and movable therein by means of adjusting screws 112, whereby the presser wheel 104 may be moved with respect to the feed wheel 103 to vary the amount of 85 pressure exerted on the tape α .

On the ends of the shafts 101, 102, opposite those occupied by the wheels 103 and 104 respectively, are gears 113 and 114, respectively, which intermesh and thereby effect synchronization of the rotary motions of the 90 wheels 103, 104. The gear 114 also meshes with a gear 115, rotatably mounted on a stud 116 secured to the head 22 of the vertically movable post 21.

95 A ratchet wheel 117 is rigidly secured to the gear wheel 115, by means of which the gear 115 is rotated, and thereby rotates the wheels 103 and 104 in intermittent steps effecting a peripheral movement thereof, substantially equal to the longitudinal spaces between the loops γ on the tape α . A pawl carrier 118 is also pivotally mounted on the stud 116, and a pawl 119 is pivotally mounted on the carrier 118, being held in operative engagement with the ratchet wheel 117 by a spring 120. A spring detent 121 engages the ratchet wheel 117 and prevents back lash thereof, after the wheel has been rotated by the pawl 119.

100 The pawl carrier 118 is oscillated about the stud 116 by a link 122, one end of which is pivotally attached to the pawl carrier 118 and the opposite end of which is pivotally attached to one end of a lever 123. The lever 115 123 is pivoted at 124 to a bracket 127, rigidly secured to the base plate 1, and is provided with a rotatably mounted cam roller 126, which is engaged by a cam 125 rigidly secured to the cam shaft 10. A spring 128 maintains 120 operative engagement between the roller 126 and the cam 127.

125 A stripper 130 is slidably mounted in the extension 30 of the post head 22, immediately adjacent the ball forming plate 35. The stripper 130 lies in a vertical plane between the plate 35 and the adjacent side of the tape feeding wheel 103 and is adapted to be moved horizontally for the purpose of stripping the loops γ from the horn 37 after the formed ball 130

has been attached thereto. The end of the stripper 130, opposite that which effects the stripping operation, is provided with a laterally extending pin 131, which is positioned 5 within a slot 132 formed in one arm 133 of a bell-crank lever 134. The bell-crank lever 134 is pivotally mounted at 135 to a block 136 secured to the bed plate 1. The opposite arm 137 of the bell-crank lever 134 is equipped 10 with a roller 138, engaged by a cam 139, rigidly secured to the cam shaft 10. A spring 140 maintains the roller 138 in operative engagement with the cam 139, and withdraws the stripper 130 to its inoperative position.

15 A vertically extending cylinder 141 is rigidly secured to the rigid bracket 50. A plunger is slidably mounted in the cylinder 141, and consists of a large head portion 142 of substantially the same diameter as that of the 20 bore of the cylinder 141, and a stem 143 of reduced diameter which projects through an aperture of substantially equal diameter thereto formed in the upper end wall of the said cylinder. A spring 144 encircles the 25 stem 143, and is confined in the cylinder between the head 142 of the said plunger and the said end wall of the cylinder. A pin 145 is secured in one side of the plunger head 142, and projects through a slot 146 formed in the 30 side of the cylinder 141, thereby limiting the movement of the plunger in the cylinder and preventing rotation of the plunger therein. The head 142 is also provided with a depending point 147 which is adapted to engage the 35 upper face of the horn 37, and thereby move the loop y into the throat 38 of the ball forming plate 35 as this plate advances to form a fringe ball.

In the operation of the machine, the cam 40 shafts 10, 11 and 12 are continuously rotating and assuming that the elements of the machine are occupying the positions illustrated in Figs. 1 to 5 of the drawings, with a loop y on the outer end of the horn 37, the 45 plunger 21, head 22, and the head extensions 30 and 31 will be raised until the ball forming plate 35, carried by the extension 30, and the opposing presser plate 41, carried by the extension 31, are in a horizontal plane coincident with that of the center of the hardened 50 steel bushing 61, through which the wire w is being advanced by the wire feeding head 72. The anvil 58 is lowered to a position immediately adjacent the projecting portion of the wire w , between the said wire and the ball 55 yarn z . The ball forming yarn z now lies between the horns 36 and 37 (see Figs. 7 and 7^a). The point 147 of the plunger 143 is in engagement with the upper face of the horn 37, between the loop y and the end of the horn. The presser plate 41 then advances toward the wire w , the wire w lying within the horizontal groove 43 in the curved end 42 thereof. The wire w is now pressed against the anvil 60 58 by the presser plate 41, and the wire-shear 65 58 by the presser plate 41, and the wire-shear

blade 62 advances and shears the wire between its beveled edge and the side of the wire guiding aperture formed in the bushing 61, (see Figs. 8 and 8^a). The presser plate continues to advance, and thereby bends the 70 wire w around the anvil 58 with the ends of the wire in alignment with the grooves 39 and 40 in the inner convergent edges of the horns 36 and 37 respectively (see Figs. 9 and 9^a). The ball forming plate 35 now advances 75 toward the anvil 58 and the ends of the wire w enter the said grooves 39 and 40, after which the anvil is withdrawn to its inoperative position, as is the wire-shear blade 62. The ball forming yarn z is now engaged by 80 the convergent edges of the horns 36 and 37, and by the wire w (see Figs. 10 and 10^a). As the plates 35 and 41 advance toward each other, one end of the wire w enters the loop y and thereafter the yarn z is forced into the throat 38 of the plate 35, the point 147 of the plunger 143 moving the loop y along the horn 36 into the throat 38 thereof, as the plate 35 advances. Further relative movement of the plates 35 and 41, toward each other, causes the 85 ends of the wire, in following the grooves 39 and 40, to be bent completely around the yarn z , to secure the yarn to the loop (see Figs. 11 and 11^a). The post 21 and the parts carried thereby are now lowered, (see Figs. 12 and 12^a), and thereby draw the yarn z through the guide 51, where it is frictionally gripped by the spring 52, thus the length of the piece of 90 yarn z which is to form a ball is measured. The yarn shear-blades 81 and 82 now advance 95 toward each other to cut the measured length of ball forming yarn (see Figs. 13 and 13^a). The stripper 130 then advances into engagement with the loop y between the tape z and the formed ball a , and as the shear blades 80 and 81, and the forming plate 35 and presser plate 41, recede the stripper 130 moves the loop y off the horn 37, and then recedes immediately thereafter. At this time, the pawl carrier 118 is turned on the stud 116 by the cam 127, the pawl 119 engages one of the notches of the ratchet wheel 117, thereby rotating said ratchet wheel and the gear 115, which, through the gears 113 and 114, rotate the tape feed wheel 103 and presser wheel 115 104, to move the loop y with the formed ball a away from the forming position and positioning a new loop y in the path of and onto the end of the horn 37. The cycle of operations just described is then repeated for the 110 successive formations of fringe balls and their attachment to the loops of the tape, which forms the body of the fringe.

The operations being entirely automatic 115 permits the machine to be operated continuously at a considerably higher rate of speed than permissible in a hand fed machine, and eliminates the necessity of employing an operator for each machine, as one operator can, with ease, look after a number of the auto- 120 125 130

matic machines, thus the production on a given number of machines is greatly increased and the cost of operation is materially reduced.

tach it to the loop; means for stripping the loop from the horn; and means for operating the tape supporting means to advance the tape and place the respective loops successively on the horn.

5 I claim:

1. In a machine for making ball fringe which consists of a body tape having loops projecting therefrom and a ball attached to each loop, the combination of a horn adapted to receive said loops; means for automatically advancing the tape to bring a loop into position on the horn; means for advancing the horn to cause one end thereof to pass through said loop; means engaging said loop to hold it in a relatively fixed position as the horn advances therewith; means cooperating with said horn for attaching a ball to said loop; and means for automatically stripping the loop from the horn.

5. In a machine for making ball fringe

20 2. In a machine for making ball fringe which consists of a body tape having loops extending laterally from one side thereof in a plane substantially at right angles to the plane of said tape and having a ball attached
25 to each loop, the combination of a horn adapted to receive said loops; means for supporting the tape in a position adjacent the horn, in a plane coincident with that of the horn, and a loop in a position on the horn; means
30 for advancing the horn into the loop; means cooperating with the horn to form a ball and attach it to the loop; and means for stripping the loop from the horn.

to said loop, and means for stripping the loop from the horn.

3. In a machine for making ball fringe
35 which consists of a body tape having loops
extending laterally from one side thereof in
a plane substantially at right angles to the
plane of said tape and having a ball attach-
ment to each loop, the combination of a horn
40 adapted to receive said loops successively;
means for supporting the tape in a position
adjacent the horn, in a plane coincident with
that of the horn, and a loop in position on the
horn; means for advancing the horn into the
45 loop; means cooperating with the horn to
form a ball and attach it to the loop; means
for stripping the loop from the horn; and
means for operating the tape supporting
means to advance the tape and place the re-
50 spective loops successively on the horn.

wheel to bring the loops successively into position on the horn.

50 successive loops successively on the horn.

4. In a machine for making ball fringe which consists of a body tape having loops extending laterally from one side thereof in a plane substantially at right angles to the 55 plane of said tape and having a ball attached to each loop, the combination of a horn adapted to receive said loops; means for supporting the tape in a position adjacent the horn in a plane coincident with that of the horn, 60 and a loop in position on the horn; means for advancing the horn into the loop; means yieldably engaging said horn and said loop to move said loop along said horn as the 65 horn advances therethrough; means cooperating with the horn to form a ball and at-

8. In a machine for making a ball of: 115

3. In a machine for making a ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn adapted to support said tape in a plane coincident with plane of said horn and a loop in a position extending transversely of said horn; a presser wheel cooperating with said feed wheel for gripping said tape; means for advancing the horn into the loop; and means for intermittently rotating said feed wheel 120 125 130

and said presser wheel to place the loops successively on the horn.

9. In a machine for making ball fringe which consists of a flat body tape having a plurality of loops extending laterally from one side thereof at predetermined intervals, the plane of each loop being substantially at right angles to the plane of said tape, the combination of a horn adapted to receive 10 said loops; a feed wheel adjacent said horn adapted to support said tape in a plane coincident with plane of said horn and a loop in a position extending transversely of said horn; a presser wheel cooperating with said 15 feed wheel for gripping said tape; means for advancing the horn into the loop; a spring loaded plunger adapted to yieldingly engage said horn for holding loop in a relatively fixed position as the horn advances thereinto; 20 and means for intermittently rotating said feed wheel and said presser wheel to place the loops successively on the horn.

10. In a machine for making ball fringe which consists of a flat body tape having a plurality of loops extending laterally from one side thereof at predetermined intervals, the plane of each loop being substantially at right angles to the plane of said tape, the combination of a horn adapted to receive 25 said loops; a feed wheel adjacent said horn adapted to support said tape in a plane coincident with plane of said horn and a loop in a position extending transversely of said horn; a presser wheel cooperating with said 30 feed wheel for gripping said tape; means for advancing the horn into the loop; a spring loaded plunger adapted to yieldingly engage said horn for holding said loop in a relatively fixed position as the horn advances 35 thereinto; a stripper operable between said feed wheel and said horn for engaging said loop and removing it from said horn; and means for intermittently rotating said feed 40 wheel and said presser wheel to place the loops successively on the horn.

43 11. In a machine for making ball fringe
which consists of a flat body tape having a
plurality of loops extending laterally from
one side thereof at predetermined intervals,
50 the plane of each loop being substantially at
right angles to the plane of said tape, the
combination of a horn adapted to receive said
loops; a feed wheel adjacent said horn adapt-
ed to support said tape in a plane coincident
55 with plane of said horn and a loop in a posi-
tion extending transversely of said horn;
pawl and ratchet mechanism for intermit-
tently rotating said feed wheel to place the
loops successively on the horn.

60 12. In a machine for making ball fringe which consists of a flat body tape having a plurality of loops extending laterally from one side thereof at predetermined intervals, the plane of each loop being substantially at 65 right angles to the plane of said tape, the

combination of a horn adapted to receive said loops; a feed wheel adjacent said horn adapted to support said tape in a plane coincident with plane of said horn and a loop in a position extending transversely of said horn; a presser wheel cooperating with said feed wheel for firmly gripping said tape; a pawl and ratchet mechanism for intermittently rotating said wheels; and means for synchronizing the rotation of said wheels. 75

13. In a machine for making ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn adapted to support said tape in a plane coincident with plane of said horn and a loop in a position extending transversely of said horn; a presser wheel cooperating with said feed wheel for firmly gripping said tape; a pawl and ratchet mechanism for intermittently rotating said wheels; means for synchronizing the rotation of said wheels; a continuously rotating shaft; and means on said shaft for oscillating the pawl with respect to the ratchet wheel of said pawl and ratchet mechanism. 85 90

14. In a machine for making ball fringe 95
which consists of a flat body tape having a
plurality of loops extending laterally from
one side thereof at predetermined intervals,
the plane of each loop being substantially at
right angles to the plane of said tape, the 100
combination of a horn adapted to receive said
loops; a feed wheel adjacent said horn adapt-
ed to support said tape in a plane coincident
with plane of said horn and a loop in a posi-
tion extending transversely of said horn; a 105
presser wheel cooperating with said feed
wheel for firmly gripping said tape; a pawl
and ratchet mechanism for intermittently ro-
tating said wheels; means for synchronizing
the rotation of said wheels; a continuously 110
rotating shaft; means on said shaft for oscil-
lating the pawl with respect to the ratchet
wheel of said pawl and ratchet mechanism;
and a spring detent engaging said ratchet
wheel. 115

15. In a machine for making ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn adapted to support said tape in a plane coincident with plane of said horn and a loop in a position extending transversely of said horn; a continuously rotating shaft; means on said shaft for advancing said horn into said loop; a stripper operable between said horn and said feed wheel and adapted to engage said 120 125 130

loop; and means on said shaft for operating said stripper to force the loop off the horn.

16. In a machine for making ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn 45 adapted to support said tape in a plane coincident with plane of said horn and a loop in a position extending transversely of said horn; a presser wheel cooperating with said feed wheel for gripping said tape; means for intermittently rotating the feed and presser wheels for advancing the tape to bring the loops successively into the horn engaging position; and means for presenting the tape to the feed wheel in a flat unwrinkled condition 50 and for retarding the said advancement of the tape. 55

17. In a machine for making ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn 60 adapted to support said tape in a plane coincident with plane of said horn and a loop in a position extending transversely of said horn; a presser wheel cooperating with said feed wheel for gripping said tape; means for intermittently rotating the feed and presser wheels for advancing the tape to place the loops successively on the horn; and means for retarding the said advancement of the tape. 65

18. In a machine for making ball fringe which consists of a flat body tape having a plurality of loops extending laterally from 70

75

one side thereof at predetermined intervals, the plane of each loop being substantially at right angles to the plane of said tape, the combination of a horn adapted to receive said loops; a feed wheel adjacent said horn 45 adapted to support said tape in a plane coincident with plane of said horn and a loop in a position extending transversely of said horn; a presser wheel cooperating with said feed wheel for gripping said tape; means for intermittently rotating the feed and presser wheels for advancing the tape to bring the loops successively into the horn engaging position; and means for presenting the tape to the feed wheel in a flat unwrinkled condition 50 and for retarding the said advancement of the tape. 55

19. In a machine for making ball fringe which consists of a flat body tape having a plurality of loops extending laterally from one side thereof at predetermined intervals, the plane of each loop being substantially at right angles to the plane of said tape, the combination of a horn adapted to receive said loops; a feed wheel adjacent said horn 60 adapted to support said tape in a plane coincident with plane of said horn and a loop in a position extending transversely of said horn; a presser wheel cooperating with said feed wheel for gripping said tape; means for intermittently rotating the feed and presser wheels for advancing the tape to place the loops successively on the horn; means for retarding the said advancement of the tape; and means for retaining the feed and presser 70 wheels in the positions to which they have been moved at the end of each advancement of the tape, to keep the tape taut between the feeding and retarding means. 75
